UNITED STATES PATENT OFFICE

2,333,317

UNIT HEATER

Richard W. Kritzer, Chicago, Ill.

Application November 1, 1940, Serial No. 363,840

8 Claims. (Cl. 98—38)

The present invention relates generally to unit heaters. More particularly the invention relates to that type of unit heater which is primarily designed to be placed and operated in a room to be heated and comprises: (1) a cabinet-like casing which has at the bottom thereof an air inlet and in its top an air outlet with a series of horizontally extending laterally spaced angularly adjustable deflector type vanes thereacross and is adapted to have air enter its interior via the inlet and then flow upwards through the outlet and past the vanes; and (2) a heating device which is disposed in the casing interior and serves when in operation to heat the air as it circulates or flows upwards through the casing.

One object of the invention is to provide a unit heater of this type which is an improvement upon, and is more efficient than, previously designed unit heaters of like character in that it embodies a fan wheel-electric motor type air circulator which is mounted over the air outlet in the top of the casing and is adapted when in use or operation to direct above and transversely across the vanes a beam or column of air under pressure in such manner that a jet action occurs whereby the circulation of air through the casing and past the heating device is materially stimulated or increased.

Another object of the invention is to provide a unit heater of the last mentioned character in which the air circulator is mounted so that it is capable of being tilted into different angular positions about a horizontal axis and is so connected to the vanes that it is conjointly adjustable with the latter.

Another object of the invention is to provide a unit heater of the type and character under consideration in which the operating connection whereby the air circulator is connected for conjoint angular adjustment with the deflector type vanes includes a turnbuckle type fitting whereby the angular position of the circulator may be varied or changed relatively to the vanes.

Another object of the invention is to provide a unit heater of the type and character heretofore mentioned in which the vanes and air circulator are mounted on a ring type frame which is rotatable in a horizontal plane in order that the vanes and circulator may be moved bodily into different horizontal positions.

A further object of the invention is to provide a unit heater which is generally of new and improved construction and is characterized by low cost of manufacture, high efficiency, and practicability.

A still further object of the invention is to provide a unit heater which has certain advantages over that which is disclosed in, and forms the subject matter of, an application for United States Letters Patent filed by me on October 10, 1940, Serial No. 360,530.

Other objects of the invention and the various advantages and characteristics of the present unit heater will be apparent from a consideration of the following detailed description.

The invention consists in the several novel features which are hereinafter set forth and are more particularly defined by claims at the conclusion hereof.

15 In the drawings which accompany and form a part of this specification or disclosure and in which like numerals of reference denote corresponding parts throughout the several views:

Figure 1 is a vertical section of a unit heater embodying the invention;

Figure 2 is a vertical transverse section taken on the line 2—2 of Figure 1 and illustrating in detail the manner in which the air circulator is mounted with respect to the angularly adjustable deflector type vanes; and

Figure 3 is a horizontal section taken on the line 3—3 of Figure 2 and showing in detail the manner in which the ring type frame for supporting the vanes and air circulator is rotatable in a horizontal plane, i. e., about a vertical axis in order to bring the vanes and air circulator into different angular positions in connection with distribution of the heated air to different points in the room to be heated.

35 The unit heater which is shown in the drawings constitutes the preferred embodiment of the invention. It is designed or adapted for use in a room or other space to be heated and as its main or principal parts comprises a box-like or cabinet type casing 4, a heating device 5 and an air circulator 6.

The casing 4 is in the form of a sheet metal shell and comprises a front 7, a back 8, a pair of sides 9, and a top 10. The sides are disposed in parallel relation and extend between, and are joined to, the side margins of the front and back. They serve to hold the front and back in spaced relation and together with said front and back define a chamber 11. The bottom margins of the

50 front, back and sides of the casing 4 define an air inlet 12 for the chamber 11. Legs 13 are provided at the lower corners of the casing and these legs serve to hold the casing in an elevated position with respect to the floor on which the heater 55 is positioned or placed with the result that the air

inlet is in communication with the bottom portion of the room to be heated. The top 10 is marginally connected to the upper margins of the front, back and sides of the casing and has in the central portion thereof a circular opening or aperture forming an air outlet 14 for the chamber 11. A ring type frame 15 carrying a series of horizontally extending laterally spaced deflector type vanes 16 is located directly above the air outlet 14. This frame is channel shaped in cross section and comprises a vertically extending web 17 and outwardly extending horizontal top and bottom legs 18 and 19. It serves to support the air circulator 6, as hereinafter described, and is carried for rotation about a vertical axis by way of a supporting ring 20 and a set or plurality of rollers 21. The ring 20 is the same in diameter as the air outlet 14 in the casing top 10 and has at the bottom thereof an integral outwardly extending annular flange 22 which is welded or otherwise fixedly secured to the portion of the casing top that defines said outlet 14. The rollers 21 are disposed within the inner periphery of the supporting ring 20 and carried by horizontally extending stub shafts on the ring. They fit between the top and bottom legs 18 and 19 of the ring shaped frame 15 and carry the frame so that it is free to be rotated in a horizontal plane. The deflector type vanes 16 are disposed within the ring type frame 15, as shown in the drawings. They are pivotally connected to the frame by way of pintles 23 and an annulus 24. The annulus fits against the inner periphery of, and is welded or otherwise fixedly secured to, the vertical web 17 of the ring shaped frame 15. The pintles 23 are located at, and project outwardly from, the ends of the vanes and are located substantially midway between the side edges of the vanes. They fit in holes in the annulus and permit the vanes to be tilted or angularly adjusted about parallel horizontal axes. When the heater is in operation, as hereinafter described, air enters the chamber 11 in the casing 4 via the air inlet 12, then flows upwards through the chamber and past the heating device 5 and finally flows upwards through the outlet 14 and past the vanes 16. The air emanating from, or flowing upwards through, the air outlet 14 is deflected by the vanes in a certain lateral direction, depending upon the position of the vanes. The vanes are connected together for conjoint adjustment or tilting by way of a horizontally extending connector bar 25 which is disposed beneath and extends diametrically across the ring shaped frame 15 and is connected to the lower side margins of the vanes by way of upstanding eyes 26 and depending apertured ears 27. The eyes are connected to the bar 25 and are spaced equidistantly apart, as shown in Figure 1. They pass through the apertures in the ears 27 and in this manner connect the vanes to the bar. The ears 27 are formed integrally with, and project downwards from, the lower margins of the vanes 16. The eyes and ears are so arranged and positioned that the vanes are held in the same angular position. When the bar 25 is shifted forwards the vanes are tilted or rotated in a counterclockwise direction, as viewed in Figure 1. When the bar is reversely shifted, that is, shifted rearwards the vanes are swung in a clockwise direction, as viewed in Figure 1, and tend partially to close the air outlet 14. By adjusting the vanes the heated air emanating from the casing may be deflected upwards or forwards. Shift of the bar 25 for vane adjusting purposes is effected or ac-

complished by way of an upstanding lever 28. The latter is located over the front portion of the ring shaped frame 15 and is connected by a pivot bracket 29 to the top leg 18 of the frame. The bracket permits the lever to be swung forwards and rearwards in a vertical plane. The lower extremity of the lever is connected to the upper marginal portion of the front or foremost vane by way of a link 30. When the lever 28 is swung forwards, as shown by dotted lines in Figure 1, the link 30 operates to tilt upwards the front vane and the connector bar 25 in turn swings or tilts the other vanes correspondingly. Forward tilting of the vanes is effected by swinging the lever 28 rearwards. By swinging the lever the vanes may be adjusted into any desired angular position. Should it be desired to change the horizontal position of the vanes it is only necessary bodily to rotate the ring shaped frame 15. The heating device 5 is located in the central portion of the chamber 11 and consists of a metal shell 31 and a burner 32. The shell defines a combustion chamber 33 and embodies a flue 34. The latter extends through the back 8 of the heater casing 4 to a point outside the room to be heated and serves to discharge or carry away the products of combustion resulting from operation of the burner 32. The latter is shown diagrammatically in Figure 1 and may be an oil or gas burner or any other type of burner member. When the burner 32 is in operation it serves to heat the shell 31 and the latter in turn heats the air as it circulates upwards through the chamber 11 in the casing 4.

The air circulator 6 is disposed over the rear portion of the ring shaped frame 15, as shown in Figures 1 and 3 of the drawings, and comprises a fan wheel 35, an electric motor 36, a guard 37 and a mount 38. The fan wheel, motor and guard are in the form of an assembly and, as herein-after described, are so carried or supported by the mount that they may be tilted into different angular positions about a horizontal axis. The fan wheel 35 is disposed within the guard 37 and consists of an elongated hub 39 and a plurality of blades 40. The hub has a pyramidal front end and embodies a socket (not shown) in its rear end. The blades are formed integrally with, and project radially from, the front end of the hub. They are angularly disposed or arranged and embody front pressure faces and rear suction faces. Preferably the fan wheel is like that which is shown in, and forms the subject matter of, United States Patent No. 1,933,948, dated November 7, 1933. The electric motor 36 is located behind the hub 39 of the fan wheel and is axially aligned therewith. It serves as the driving medium for the fan wheel and embodies an armature shaft 41 which extends into the socket in the rear end of the fan wheel hub 39 and is keyed or otherwise fixedly secured to the hub. When the motor 36 is in operation it serves to drive the fan wheel 35 and during drive or operation of the fan wheel the suction faces of the blades direct inwards and forwards the air surrounding the motor 36 and deliver such air into the path of the pressure faces of the blades. The latter in turn project or propel the air forwards in beam or column form, as illustrated by dotted lines in Figure 1. The guard 37 is formed of concentric wire cross pieces and surrounds the fan wheel and motor. It operates as a protecting device in that it serves to prevent objects being brought at random into contact or engagement with the blades 40 of the fan wheel. The central portion of the casing of

the electric motor 36 is secured to the rear portion of the guard. The mount 38 of the air circulator 6 comprises a bracket 42 and a U-shaped member 43. The bracket 42 is fixed to the top leg 18 of the frame 15 and projects inwards from the rear portion of the frame interior. It is in the nature of a platform and constitutes a supporting medium for the U-shaped member 43. The latter is located directly above the bracket and serves as a connecting medium between the bracket and the assembly of fan wheel, motor and guard. A vertically extending bolt 44 extends through the central portion of the member 43 and also through the bracket and serves to hold the U-shaped member in a position wherein it extends at right angles to the deflector type vanes 16. The upper ends of the U-shaped member 43 are connected by pivotal connections 45 to diametrically opposite side portions of the guard 37. Such connections are horizontally aligned and permit the assembly of fan wheel, motor and guard to be tilted or angularly adjusted about a horizontal axis. When the assembly is vertically positioned, as shown in Figure 1 and the vanes 16 are tilted or inclined forwards and upwards the beam or column of air under pressure which emanates from the fan wheel during operation of the electric motor moves or flows transversely across the vanes 16 and produces pronounced suction which results in an effective and efficient up-flow of air through the casing 4, and in addition draws the heated air emanating from the outlet 14 into the beam or column. The beam or column of air under pressure together with the heated air travels across the room to be heated and in this manner effects heating of the air in the room. Because the circulator is located inwards of the ring shaped frame 15 it not only directs the heated air in beam or column form across the room to be heated but also sucks or directs the heated air in back of the fan wheel upwards from the chamber 11 and in this manner also serves to stimulate up-flow or circulation of air through the casing and past the heating device 5. By reason of the fact that the mount for the circulator is carried by the ring shaped frame 15 the circulator is shiftable into different horizontal positions with the vanes. For the purpose of connecting the assembly of fan wheel, motor and guard for conjoint tilting or angular adjustment with the vanes 16 a connection in the form of a link 46 is provided. This link overlies and extends diametrically across the frame 15 and includes in the central portion thereof a turnbuckle 47. The front end of the link 46 is pivotally connected to the upper end of the lever 28. The rear end of the link is pivotally connected to the lower portion of the guard 37 of the air circulator 6. When the lever 28 is swung forwards in order to open or tilt upwards the vanes 16 the link 46 operates correspondingly and conjointly to swing or tilt upwards the assembly of fan wheel, motor and guard. When the lever 28 is swung rearwards in connection with closing or clockwise angular adjustment of the vanes the assembly is caused conformably to tilt downwards. Because of the link 46 between the lever 28 and the lower portion of the guard, the assembly is always in a predetermined angular position with respect to the vanes. The turnbuckle 47 permits of elongation or contraction of the link 46 and constitutes means for adjusting the angular position of the assembly relatively to the vanes. Should it be desired to increase

the angle at which the assembly extends with respect to the vanes the turnbuckle is manipulated or adjusted so as to decrease the overall length of the link 46. In the event that it is desired to decrease the angle at which the assembly extends relatively to the vanes the turnbuckle 47 is manipulated or adjusted so as to increase the length of the link 46. The link 46 constitutes simple means for connecting the assembly and the vanes for conjoint tilting or angular adjustment and the turnbuckle 47 constitutes means for varying the angular position of the assembly relatively to the vanes. When it is desired to direct the heated air emanating from the air outlet 14 upwards the lever 26 is swung forwards. When it is desired to direct the beam or column of heated air to one side of the heater casing 4 it is only necessary bodily to rotate the ring shaped frame 15. Such movement or operation, as hereinbefore pointed out, serves bodily to adjust the vanes and air circulator horizontally.

The herein described unit heater is extremely efficient in operation and this is primarily attributable to the fact that with the deflector type vanes 16 arranged at an angle with respect to the air circulator the circulator creates, due to the resulting jet action, such suction within the casing that the air in the casing circulates rapidly upwards therethrough. By having the circulator and the vanes conjointly angularly adjustable but a single control movement is necessary to change the direction of the beam or column of heated air. When the heating device 5 of the heater is inoperative due to the room in which the heater is disposed being at a predetermined temperature the air circulator 6 may, if desired, be utilized independently for air circulating purposes. The heater may be produced at a comparatively low cost because of the simplicity of its design.

The invention is not to be understood as restricted to the details set forth since these may be modified within the scope of the appended claims without departing from the spirit and scope of the invention.

Having thus described the invention what I claim as new and desire to secure by Letters Patent is:

1. The combination with a box-like casing adapted to have air circulate upwardly through it and provided with an upwardly facing air outlet at the top thereof, of a series of parallel laterally spaced deflector type vanes across the outlet for directing the air emerging from said outlet, pivotally supported to swing into different angular positions and connected together for conjoint angular adjustment, an air circulator positioned exteriorly of the casing and directly above the outlet and including an assembly of fan wheel and electric motor and a mount whereby the assembly may be tilted vertically into different angular positions, and a connection between the assembly and the vanes for connecting them together for conjoint angular adjustment.

2. The combination with a box-like casing adapted to have air circulate upwardly through it and provided with an upwardly facing air outlet at the top thereof, of a series of parallel laterally spaced deflector type vanes across the outlet for directing the air emerging from said outlet, pivotally supported to swing into different angular positions and connected together for conjoint angular adjustment, an air circulator positioned exteriorly of the casing and directly above

the outlet and including an assembly of fan wheel and electric motor and a mount whereby the assembly may be tilted vertically into different angular positions, and a connection between the assembly and the vanes operative to connect them together for conjoint angular adjustment and including means for adjusting the angular position of the assembly relatively to the vanes.

3. The combination with a box-like casing adapted to have air circulate upwardly therethrough and provided with an upwardly facing air outlet at the top thereof, of a series of parallel laterally spaced deflector type vanes for deflecting or directing the air emanating from the outlet, extending horizontally across the outlet and pivotally supported at the ends thereof to swing into different angular positions, means for conjointly shifting the vanes into different angular positions including a control element manipulable from the exterior of the casing, an air circulator for directing the air in beam form away from the casing after it passes through the outlet positioned exteriorly of the casing and adjacent the outlet and including an assembly of fan wheel and electric motor and a mount whereby the assembly may be tilted into different angular positions about a horizontal axis, and an operating connection between the assembly and the control element for connecting the assembly for conjoint angular adjustment with the vanes.

4. The combination with a box-like casing adapted to have air circulate upwardly therethrough and provided with an upwardly facing air outlet at the top thereof, of a series of parallel laterally spaced deflector type vanes for deflecting or directing the air emanating from the outlet, extending horizontally across the outlet and pivotally supported at the ends thereof to swing into different angular positions, means for conjointly shifting the vanes into different angular positions including a control element manipulable from the exterior of the casing, an air circulator for directing the air in beam form away from the casing after it passes through the outlet, positioned exteriorly of the casing and adjacent the outlet and including an assembly of fan wheel and electric motor and a mount whereby the assembly may be tilted into different angular positions about a horizontal axis, and an operating connection including a turnbuckle and extending between the assembly and control element for connecting the assembly and vanes for conjoint adjustment.

5. The combination with a box-like casing adapted to have air circulate upwardly through it and provided with an upwardly facing air outlet at the top thereof, of a frame adjacent the

outlet mounted to rotate about a vertical axis and having a series of laterally spaced deflector members thereacross, and an unenclosed air circulator for directing the air in beam form away from the casing after it passes through the outlet and past the members mounted wholly exteriorly of the casing and on the frame and shiftable bodily into different horizontal positions in response to shift of the frame.

10 6. The combination with a box-like casing adapted to have air circulate upwardly through it and provided with an upwardly facing air outlet at the top thereof, of a frame adjacent the outlet, mounted to rotate about a vertical axis and having a series of laterally spaced deflector members thereacross, and an unenclosed air circulator for directing the air in beam form away from the casing after it passes through the outlet and past the members, disposed above the outlet and wholly exteriorly of the casing and including an assembly of fan wheel and electric motor and a mount between the assembly and the frame whereby the assembly may be tilted into different angular positions for beam adjusting purposes.

7. The combination with a box-like casing adapted to have air circulate upwardly through it and provided with an upwardly facing air outlet at the top thereof, of a frame adjacent the outlet mounted to rotate about a vertical axis and carrying thereacross a series of laterally spaced horizontally extending angularly adjustable deflector type vanes, and an unenclosed air circulator for directing the air in beam form away from the casing after it passes through the outlet and past the vanes mounted wholly exteriorly of the casing and on the frame and shiftable bodily into different horizontal positions in response to shift of the frame.

40 8. The combination with a box-like casing adapted to have air circulate upwardly through it and provided with an upwardly facing air outlet at the top thereof, of a ring shaped frame around the outlet mounted to rotate about a vertical central axis and carrying thereacross a series of laterally spaced horizontally extending angularly adjustable deflector type vanes, means associated with the frame for connecting the vanes together for conjoint adjustment, and an air circulator for directing the air in beam form away from the casing after it emerges from the outlet, disposed over the frame and including an assembly of fan wheel and motor and a mount between the assembly and the frame whereby the assembly is permitted to tilt into different angular positions about a horizontal axis, and means connecting the assembly to the vanes for conjoint adjustment.

RICHARD W. KRITZER.
